UNITED STATES PATENT OFFICE

99,390

DESIGN FOR A BASE FOR A LAMP OR SIMILAR ARTICLE

James R. Clifford, Chicago, Ill.

Application January 4, 1936, Serial No. 60,419

Term of patent 3½ years

To all whom it may concern:

Be it known that I, James R. Clifford, a citizen of the United States, residing in Chicago, in the county of Cook and State of Illinois, have invented a new, original, and ornamental Design for a Base for a Lamp or Similar Article, of which the following is a specification, reference being had to the accompanying drawing, forming a part thereof.

Fig. 1 is a perspective view of a base for a lamp or similar article, showing my new design; and
Fig. 2 is an end view of the same.

I claim:

The ornamental design for a base for a lamp or similar article as shown.

JAMES R. CLIFFORD.
